(57) **CLAIM**

The ornamental design for a cartridge for inhaler, as shown and described.

DESCRIPTION

FIG. 1 is a front elevation view of a cartridge for inhaler;
FIG. 2 is a right elevation view thereof;
FIG. 3 is a rear elevation view thereof;
FIG. 4 is a left elevation view thereof;
FIG. 5 is a bottom plan view thereof;
FIG. 6 is a top plan view thereof;
FIG. 7 is a perspective view from the top, front and right corner thereof;
FIG. 8 is a perspective view from the bottom, front and left corner thereof; and,
FIG. 9 is a perspective view from the top, front and right corner thereof.

The broken lines in the drawings illustrate portions of the cartridge for inhaler that form no part of the claimed design.

1 Claim, 9 Drawing Sheets
